UNITED STATES PATENT OFFICE

CHARLES HELLING, OF MILWAUKEE, WISCONSIN

FINISHING AND POLISHING TOOL

Application filed October 26, 1929. Serial No. 402,670.

This invention relates to improvements in portable finishing and polishing tools.

At the present time various types of machines comprise castings which must be finished before painting or lacquering, and it is customary to first fill the pores of the casting with a conventional iron filler, applied in a plastic or semi-liquid state. After the filler dries, the same must be sanded or smoothed off by a suitable abraiding tool, such operation resulting in creating considerable dust, which is injurious and objectionable to the workmen.

It is, therefore, the primary object of the present invention to provide a simple, inexpensive, portable abraiding or grinding tool, which materially facilitates polishing off the iron filler from a casting, in that the same may be readily manipulated in corners and over irregular surfaces, and which provides means for collecting the dust and small particles of filler, ground off the casting, and conducting the same to any suitable source through means of suction. Thus, the cost of finishing castings is materially reduced and the operator is not subject to the injurious effects of rising dust and small particles removed from the casting.

Also, by this process, the casting, or such parts as are exposed to view, are left with a smooth finish, which more readily takes paint or lacquer, thus materially improving the appearance of the casting.

Another object of my invention is the provision of a polishing and finishing tool wherein different sized polishing and finishing rolls may be applied to the drive shaft, and the shaft is so mounted as to be automatically stabilized and is so arranged that any size of polishing or finishing roll can be quickly and readily mounted thereon.

A further object of the invention is the provision of a tool of the above character wherein the polishing and finishing rolls are mounted in a suitable hood, and the hood is detachably connected to the body of the device in such manner that it may be readily interchanged for different sizes in accordance with the size of the finishing or polishing rolls which are to be used.

With these and other objects in view, the invention consists in the novel features of construction, the combination and arrangement of parts hereinafter more fully set forth, pointed out in the claims and shown in the accompanying drawings wherein:

Figure 1 is a longitudinal section taken through my improved polishing and finishing tool;

Figure 2 is a front end elevation;

Figure 3 is a transverse section on the line 3—3 of Figure 1; and,

Figure 4 is a detail section illustrating the manner of clamping the detachable hoods to the body of the device.

In carrying out my invention, I provide a tubular body part 1 having a tubular extension 2 at one end to which is connected a conduit 3, for carrying off the loose particles which are removed from the casting during the finishing and polishing operation.

This body member 1 is provided at one side thereof with spaced ears 4 and positioned between the ears are the ends of a U-shaped handle member 5, the handle member 5 being bolted or otherwise secured to the ears 4. As will be noted in Figure 3, this tubular body member 1 is substantially oval in shape, and one side thereof, particularly the side opposite the handle portion 5, is formed with a channel 6, and arranged in opposed relation with this channel is a removable cover 7 which may be bolted or otherwise secured to the body 1.

It will be noted from the showing in Figure 3, that the channel 6 and arcuate cover 7 form a circular chamber extending the entire length of the body 1 and arranged in this chamber at each end thereof, are tubular bearing members 8, having diametric pins 9 carried thereby which are rotatably mounted in suitable bearings at the side of the cylindrical portion.

A bearing chamber is also formed intermediate the ends of the cylindrical part and arranged therein is a collar 10 having discs 11 arranged upon opposite sides thereof which bear against friction members 12. These friction members 12 are maintained in position against the discs 11 by means of spaced ribs 13 and 13', so as to maintain the collar 10 in a substantially cen-

tral position.

tral position with respect to the ends on the cylindrical housing.

Extending into one end of the cylindrical housing formed by the channel 6 and arcuate cover 7, is a tubular shaft 14 which passes through the rockable bearings 8 and through the collar 10. This tubular shaft projects beyond the other end of the circular member and is exteriorly threaded, as shown at 15, 10 for reception of a coupling member 29.

In view of the fact that the tubular shaft 14 is of considerable length, it is essential that the bearing be properly aligned to avoid undue wear and vibration of the shaft. Therefore, I provide the pivotally mounted bearings 8, which readily align themselves with the shaft 14.

One end of the shaft 14 is connected to a flexible drive shaft 18 by means of the universal connection 19. While I have described a universal connection between the driving shaft and the tubular shaft, it will be apparent that any other suitable connection may be used.

25 The forward end of the housing 1 is normally opened and it is apparent from the foregoing construction that polishing and finishing rolls can be detachably connected to the outer end of the tubular shaft 14. These 30 rolls may be of different diameters and of different lengths, and in order to provide for suitable suction to draw the dust and smaller particles upwardly into the body 1, it is necessary to provide hoods for enclosing the different sizes and different lengths of rolls, and to this end I provide a detachable hood 19 at the outer end of the body 1.

It will be noted that the body 1 is provided with a lateral flange 20 and the hood 19 is 40 provided with a similar flange 21, whereby these flanges are adapted to be arranged in intimate relation and detachably connected so that the different hoods may be readily inter-changed.

45 In connecting the hoods to the body 1, I provide a U-shaped engaging element 22 which is wide enough to fit snugly over the opposed flanges and embrace both of them. One side of the U-shaped members 22 is provided with spaced perforated ears 23 and the side of the clamp carrying these ears has a slot 24 disposed directly between the ears. Pivotally mounted between the ears 23 is an engaging cam 25 having a handle portion 26 55 whereby this cam may be rocked upon its pivot and contact with one of the flanges 20 or 21 for securing the U-shaped members 22 in position and thus retain the hood upon the end of the body 1.

60 The interior of the hood 19 communicates directly with the body 1 and the lower side of the hood is provided with a longitudinal opening 27. The outer end of the hood is normally closed by means of a removable cap 28 65 which may be readily fitted into the end of the

hood or engaged over the exterior thereof and provided with suitable means for detachably connecting the cap to the hood.

As previously explained, the outer end of the shaft 14 receives the internally threaded coupling 29 by means of which the abrading or finishing rolls are attached. As will be noted in Figure 1 of the drawings, the finishing rolls comprise a body portion 31 in which is secured a tubular core 30 projecting beyond the ends of the body portion and exteriorly threaded. One end of the core 30 is threaded into the coupling 29, thus securing the roll to the shaft 14.

In some instances, deep castings or other conditions require that the finishing roll 31 be extended some distance from the main body 1, in order that otherwise inaccessible parts of the casting may be reached. In such event, an extended coupling 29 is utilized, and in order to provide the necessary rigidity between the finishing roll and the shaft 14, the extension rod 34 is slidably mounted within the tube 14 and provided with an outer threaded end 40, which is secured to an outer 90 finishing roll, as will be hereinafter described.

As best shown in Figure 1, the finishing rolls are formed in two sections in order that a suitable bearing may be provided for the same. This is accomplished by the provision of an end roll 33 provided with a core 38 threaded upon the outer end 39 of the core 30, the core 38 also being provided with a restricted threaded recess 40 for reception of the rod 34. Mounted on the core 30 between the rolls 33 and 31 is an anti-frictional bearing 36 which is carried in the bearing plate 37 loosely mounted within the hood 19 and held against tipping by the foot 37', which 100 engages the inner wall of the hood.

Thus it will be seen that any strain exerted upon the finishing roll, as the same is forced into contact with the casting, will be taken up by the bearing 36. This is very essential 110 where the rolls are extended, or where an exceedingly long roll is employed, it being understood that in such instances a longer hood is substituted for the hood 19, as heretofore described.

115 It will be noted in Figure 1 that the rolls 33 and 31 are covered with any suitable abrasive or binding material 41, such as emery, carborundum, or the like, and it will also be noted that the end face of the roll 33 is likewise covered, which permits such base to be utilized upon flat work by removing the cover 28. While the rolls 31 and 33 are covered in any suitable manner, it is proposed to coat the same with a suitable adhesive, after 120 which abrasive material is sprinkled over their exposed surfaces.

125 When the polishing and finishing rolls or drums are mounted in position within the hood 19, it will be noted that a portion there- 130

of extends below the lower part of the hood and projects through the slot or opened lower portion 27 so that considerable surface on these polishing and finishing rolls will be exposed below the hood for contact with the casting, which is being operated upon.

It will be apparent from the foregoing that I have provided a very simple and inexpensive tool which is especially adapted for use in finishing off metal castings, and it will take the place of the hand sanding operation carried on at the present time in order to provide a comparatively smooth finish to the exterior of the casting.

As the conduit 3 is connected to a source of suction to draw the air through the body 1, it will be apparent that the passage of air will be through the opening or slot 27 of the hood 19 and thus the air will be drawn upwardly carrying the particles, which are removed from the casting, up through the hood, and thence to the body 1 and out through the conduit 3, where it may be conveyed to any suitable receptacle, thus removing the fine particles of the casting and the fine dust arising from the finishing and polishing operation so as to eliminate the necessity of the operator breathing these fine particles into their system.

As stated heretofore, the hood 19 can be readily interchanged for hoods of different lengths in accordance with the length and size of finishing and polishing rolls to be used, and it will be noted that these hoods can be quickly interchanged through the medium of the clamping element used.

In order to maintain the tubular bearing 8 in position, it will be noted that the cylindrical housing is formed at a point adjacent each end thereof with inwardly disposed flanges 42, and at each end of the members 8, I provide bearing discs 43, and between the discs 43 and the ends of the cylindrical housing and the flanges 42 are friction members 44. The cylindrical housing is preferably filled with a lubricant so that all rotative parts therein will be thoroughly lubricated and these friction members 44 at the ends of the bearings are preferably of a type which will maintain the lubricating fluid in the housing.

The device is not only simple in construction but is one which will be of substantial value as a labor saver in view of the fact that the sanding operation for metal castings can be very quickly and readily carried out by the use of this tool and the operating and upkeep cost of the same is very inexpensive.

While I have shown and described the preferred embodiment of my invention, it will be apparent that slight changes may be made in the construction when putting the invention into practice without departing from the spirit of the same or the scope of the appended claims.

I claim:

1. A tool of the class described including a tubular body, a cylindrical chamber at one side of the body, a tubular shaft passing through the cylindrical chamber, rockable bearings within the chamber for supporting the shaft, a rod mounted in the tubular shaft and projecting beyond the outer end thereof, a detachable hood at one end of the body, polishing rolls arranged within said hood, and means for removably mounting the polishing rolls upon the tubular shaft and rod with a portion thereof projecting beyond the exterior of the hood.

2. In a tool of the class described, a tubular body, a conduit connected to one end thereof, a cylindrical housing at one side of the body, a tubular shaft extended through the housing, rockable bearings for supporting said shaft, a rod within the shaft and projecting beyond one end thereof, polishing rolls, and means for detachably connecting the polishing rolls to the shaft and rod.

3. A tool of the class described including a tubular body, a conduit connected to one side thereof, a cylindrical housing at one side of the body, a tubular shaft mounted in the housing and projecting beyond the end of the housing adjacent the open end of the body, rockable bearings for supporting said shaft within the housing, a hood detachably connected to the open end of the body and having a longitudinal slot in the lower side thereof, polishing rolls and means for detachably connecting the polishing rolls to the projecting end of the shaft with a portion of the polishing rolls projecting through the slot in the hood.

4. A tool of the class described including a tubular body, a conduit connected to one end thereof, a tubular shaft supported at one side of the body, a rod within said shaft, a hood detachably connected to the end of the body opposite the conduit and having a longitudinal slot, a removable cap for the outer end of the hood, a bracket within the hood, a bearing supported by said bracket for receiving the outer end of the rod, polishing rolls, and means for detachably connecting the polishing rolls to the outer ends of the shaft and rod whereby a portion of the polishing rolls will be exposed through the slot in the hood.

5. A tool of the class described including a hollow body, a conduit connected to one end thereof, a driven tubular shaft supported at one side of the body and parallel therewith, a rod mounted within the shaft and projecting beyond one end thereof, a hood detachably connected to the end of the body opposite the conduit and formed with a longitudinal slot, a removable cap for the outer end of the hood, polishing rolls, and means for detachably connecting the polishing rolls to the shaft and rod whereby a portion of

said rolls are to be exposed through the slot in the hood.

6. A tool of the class described including a hollow body, a supporting handle at one side thereof, a driven shaft at the other side, a conduit connected with one end of the body, a lateral flange at the other end of the body, a detachable hood having a lateral flange to abut the flange of the body, a U-shaped clamp 10 engaging over said abutting flanges, a cam member carried by said U-shaped member for retaining said U-shaped member in position, a polishing roll, and means for detachably connecting the polishing roll to one end of the shaft.

15 7. In a tool of the class described, a tubular body, a suction conduit connected to one end thereof, a cylindrical housing carried by the body, a tubular shaft extending through the 20 housing, rockable bearings for supporting said shaft, a rod within the shaft and projecting beyond one end thereof, a pair of spaced polishing rolls connected with said shaft, said rod being slidably mounted within said shaft 25 and connected to the outer of said rolls, a bearing positioned between said rolls, and a hood connected to said housing for surrounding a portion of said rolls.

8. In a tool of the class described, a hollow body, a suction conduit connected to one 30 end thereof, a hood connected to the opposite end thereof, means for clamping said hood to said body, a shaft carried by said body, a coupling member secured to one end of said shaft, abrasive rolls carried by said coupling member and positioned partially within said hood, and a bearing carried by said hood and positioned between said rolls.

40 In testimony that I claim the foregoing I have hereunto set my hand at Milwaukee, in the county of Milwaukee, and State of Wisconsin.

CHARLES HELLING.
